Deutsche Waffen-und Munitionsfabriken Aktiengesellschaft, a corporation of Germany

Application June 15, 1936, Serial No. 85,443
In Germany May 5, 1935

4 Claims. (Cl. 18—16)

This invention relates to pastille or like presses for pressing powdered charges in a plurality of capsules or the like under a definite and regulable pressure.

5 During making of the cores of illuminating and priming charges as well as the fillings for explosion capsules and primers or percussion caps said cores or fillings are subjected to a previous exactly defined pressure in order to attain a definite de-
gree of density of said cores or fillings.

In mechanically actuated presses used for this purpose, a press-plunger serves to suddenly compress said cores or fillings with a uniform amount of pressure. In presses of this kind, however, 15 there is the disadvantage, that the air contained in the powder-charge cannot escape to a sufficient extent during the operation of pressing, with the result that the working of the press will be retarded and that the cores of fillings obtained 20 thereby are only insufficiently compressed.

In order to increase the working capacity of the press and to further improve its mode of operation, according to my invention I propose to construct the press to permit the simultaneous pressing of a set or plurality of such cores or fillings by a single working step of the press with the aid of hydraulic or pneumatic means. By my invention the aforementioned disadvantage inherent to mechanically operated presses is successfully 25 avoided, proper escapement of the air contained in the powder charge being attained during the gradually increasing operating pressure in a hydraulically or pneumatically operated press.

In order to properly apply and utilize the hydraulic or pneumatic pressure, according to my invention I make use of metallic bellows-chambers as a pressure transmitting means. In addition to this, according to my invention I provide further special devices for imposing upon said bellows-chambers a load or pressure which may be regulated within any desired limits, said load or pressure and the regulation thereof being effected by means of a weight or spring acting on said devices. According to my invention, the 30 press is further equipped with a contrivance permitting to attain proper equalization of the pressure exerted onto said cores or fillings by the press-plungers, such equalization of pressure being especially of advantage if one or several of the 35 cores or fillings that had been preliminarily compressed to an insufficient extent, or in case cores or fillings of improper weight have to be worked in the press. By means of the aforesaid contrivance it will be possible to always compress the said 40 cores or fillings with the required uniform pres-

sure, irrespective of the fact, whether one or several of the set of cores or fillings to be worked in the press are missing or whether they are not of the proper weight. This contrivance consists essentially of a system of press-plungers and 5 double-armed levers co-operating with each other, the leverage of the several levers being properly chosen to attain a uniform distribution of the pressures exerted by the press-plungers on the individual cores or fillings.

In order to regulate the hydraulic or pneumatic pressure serving for the operation of the press within the desired limits, according to my invention a second bellows-chamber is associated with the former and adapted to be under the action of 10 a properly adjustable spring- or weight-actuated pressure device. In addition to this, my novel press is provided with an optical or acoustic signalling or indicating device which may be operated either mechanically or electrically to indicate the condition of the set of cores or fillings 15 at a time worked in the press, and more especially, to indicate whether a core or filling is missing or whether some defect is present in one or the other 20 element of the set.

In the drawing which forms part of this specification I have represented an example of a construction of my press, Fig. 1 being a front-view, Fig. 2 a side-view and Fig. 3 a plan-view thereof. Fig. 4 is a view of the indicating or signalling 25 device forming part of the press.

The construction and operation of my novel press is as follows.

Motion is transmitted to the press by means of a driving shaft 1 carrying a worm 2 in mesh with a 30 worm-wheel 3 on the main shaft 4. The latter is provided on either end thereof with a cam-disk 31, each of said cam-disks engaging with one end of a bell-crank 32, thus rocking the latter during 35 rotation of the former. The other end of either bell-crank 32 extends into a slot 33 in either of the bolts 34, thus imparting downward motion to said bolts. The bolts 34 are connected with each other by means of a transverse pressure-bar 39 carrying 40 the system of levers operating the press-plungers 45 11. The latter are mounted in a transverse guide member 38 preferably of the form of a plate, said guide member being likewise carried by said bolts 34 so that downward operating motion of the latter is likewise imparted to said guide member 40 38. The press-plungers 11, thus, upon downward motion of said guide member 38 and said bolts 34 will be pressed against the cores or fillings 10 for the charge, priming caps or the like, thus compressing the same. The cores or fillings 50 55

18, moreover, are seated in the press-plate 9 and placed into the press together with said plate onto the pressure member proper 37 of the press. Centering pins 49 permit exact adjustment of the 5 press-plate 9 and of the cores or fillings 10 thereon with respect to said guide-member 38 and the press-plungers 11.

Upon completed downward stroke of the press-plungers 11, the latter are pressed at first with a 10 slight pressure against the fillings 10 and thereupon the under bellows-chamber 17 is compressed by action of the cam-disks 5 and 6 on the main shaft 4. The under end of the upper as well as the upper end of the under bellows-chamber, 36, 15 7 are firmly connected to an intermediate or central member 35 interposed therebetween, said member 35 being fixed on either end by means of screws or otherwise to the lateral walls or pillars 41 of the press. Both bellows-chambers 7 and 36 are connected with each other by means of a 20 supply conduit and filled with operating liquid. Upon compression of the under bellows-chamber 7 by action of the cam-disks 5 and 6 thereon, the operating pressure is transmitted from the 25 under to the upper bellows-chamber, thus expanding said upper chamber 36 and forcing the pressure member or plate 37 as well as the press-plate 9 upward to cause compression of the cores or fillings 10 by the press-plungers 11.

30 If the bellows-chamber 7 is still further compressed, the liquid contained therein will flow through the conduit 12 into another bellows-chamber 13 causing the latter to expand and move forward with its front part and the roller 35 15 imparting rotation to the worm 16. The shaft of said worm 16 carries a disk 17 having a steel-band 18 fastened at one of its ends to the periphery of said disk, said steel-band acting on a bell-crank 19 which is provided with a weight 40 resting adjustably on the longer arm thereof.

During compression of the bellows-chamber 36 the press-plungers 11 will more firmly abut against the fillings 10 and the plate 9 in which they are seated, thus causing the operating pressure to be transmitted from chamber 36 through 45 conduit 12 to the bellows-chamber 13 with the result that the latter will expand and rotate the worm 16 and the disk 17, thus adjusting the bell-crank 19 by means of the steel-band 18. The 50 lever 19, however, can only be adjusted, if it is able to overcome the torque acting thereon due to the weight 20. In this manner it will be possible to impart to the press-plungers 11 a constant and uniform final pressure owing to the 55 action of said weight. This pressure may be regulated within any desired limits by adjusting the weight 20 on the longer arm of the bell-crank 19.

In case one or more of the cores or fillings to 60 be worked in the press are missing, the same operating pressure may be imparted to the remaining cores or fillings on the plate 9 as in case all cores are present in the latter by properly interconnecting the press-plungers by means of a special combination or system of levers, as shown at 65 the upper part of Fig. 1.

The distribution of pressure in this case takes 70 place in the following manner. Assuming a total operating pressure of 100 kg., and even distribution of pressure over the plungers, each of the five plungers 11 would receive a pressure of 20 kg., which is attained by properly dimensioning the lengths of the arms of the first or main lever 22 pivoted to a bolt 21 on the transverse pressure bar 39. In accordance with the lengths of the 75

arms of the several levers there will be obtained a pressure of 40 kg. on the right-hand half and a pressure of 60 kg. on the left-hand half of the plunger and lever system. This pressure of 60 kg. on the left-hand half now is transmitted to 5 the ends of lever 23 and by properly dimensioning the arms of this lever, the right-hand end will act with pressure of 20 kg. and the left-hand end with a pressure of 40 kg. These two pressures of 20 and 40 kg. are transmitted onto the 10 pivot point 24 of the lever 25 with arms of even length, thus imparting to each of the two plungers connected thereto a pressure of 20 kg. If, for instance, these two plungers on the left-hand side of the plunger and lever system do not find 15 an abutment on account of cores or fillings missing at these places, only 20 kg. of the said 60 kg. which act on the left-hand end of lever 22 will be transmitted to the middle plunger of the system. The several plungers 11 are mounted movably in 20 the transverse guide 38 under the action of cylindrical spiral springs 42 that are compressed during downward motion of said plungers. If one of the plungers, owing to the missing of the respective core or filling, does not find an abutment during operation of the press, the respective cylindrical spiral spring will be compressed and this pressure, amounting in the present case to 20 kg., will be transmitted to the transverse 25 guide 38. 30

The aforescribed system of levers and plungers will effect an automatic equalization of the operating pressures of the several plungers, with the result that each of the set of cores or fillings worked at a time in the press, irrespective of the 35 fact whether one or more of the cores or fillings of the set are missing, will invariably be acted upon by an even uniform operating pressure which may be chosen in accordance with the present requirements. 40

In order to supervise or control the operation of the press, there is provided a special indicating or signalling device shown in Fig. 4. This device consists of levers in the form of pointers that are rotated backward whenever a plunger 11 45 acts upon a core or filling and cause a number to appear and disappear in a window above the respective plunger, the appearing or disappearing number indicating the presence or absence of the respective core or filling. This pointer 50 may also be constructed in such a manner that in the absence of a core or filling of the set an electrical contact is made or broken causing ringing of the bell or effecting an optical signal. 55

The amount of the operating pressure at a time prevailing in the press may be indicated by a pressure-gauge 26 connected to the above mentioned conduit 12. Instead of a hydraulic transmission of the operating pressure to the press-plungers, evidently also a pneumatic transmission 60 may be employed. In the latter case the several bellows-chambers as well as the other operating members of the press may be fully retained.

The distance between the press-plate 9 and the unit formed by the pressure bar 39, the guide member 38 and the press-plungers 11 may be adjusted by rotating the hand-wheel 43 and therewith the shaft 27 carrying two bevel-gears 28 rigidly secured thereon, each meshing with 70 a bevel-gear 29 rigidly secured to a threaded bushing 30, the transverse pressure bar 39 and the transverse guide 38 forming a closed frame together with said bushings 30. The operating pressure of the press may thus be varied within 75

any desired limits. This adjusting device, in addition, permits simultaneous adjustment of all press-plungers 11, without necessitating any individual adjustment of the latter.

5 The herein described press and its operating members may be modified in various ways without departing from the spirit of my invention and sacrificing any of its advantages. Thus, for instance, instead of employing single bellows-chambers also chambers formed by a plurality of bellows, arranged side by side, may be used, as will be evident to anyone skilled in the art. Furthermore, instead of a liquid operating medium also air may be used in said bellows-chambers, a broad principle of my invention consisting in the use of bellows-chambers in connection with a system of double-armed levers and press-plungers in presses of the character described.

I claim:

20 1. A pastille or like press for completing the pressing of sets of powdered fillings or preliminarily pressed cores or the like, said press comprising a pressure member including a plurality of metallic bellows chambers containing a pressure medium, an adjustable tension-actuated device associated with said pressure member for regulating the operating pressure thereof, a press plate including means for receiving and retaining said fillings or cores thereon cooperating with said pressure member, press plungers for compressing said fillings or cores, and pressure equalizing means cooperating with said plungers and comprising a system of double-armed levers for equally dividing the pressure upon said plungers.

25 30 35 2. A press as specified by claim 1, including a member for guiding said press plungers, a transverse pressure bar connected to said guide member and spaced a fixed distance therefrom, and resilient means interposed between said guide

member and each of said press plungers for transmitting a respective part of the operating pressure onto said guide member and said transverse pressure bar if a filling or core of the set is missing from said pressure plate.

5 10 15 3. A press as specified by claim 1, including a guide member for said press plungers, a transverse pressure bar connected to said guide member and spaced a fixed distance therefrom, and resilient means interposed between said guide member and each of said press plungers for transmitting a respective part of the operating pressure onto said guide member and said transverse pressure bar if a filling or core of the set is missing from said pressure plate, said adjustable tension-actuated device providing said bellows chambers with an even and uniform operating pressure.

20 25 30 35 4. A press as specified by claim 1, including a guide member for said press plungers, a transverse pressure bar, connected to said guide member but spaced at a fixed distance therefrom, said equalizing means and said press plungers being secured to said transverse bar, resilient means interposed between said guide member and each of said press plungers for transmitting a respective part of the operating pressure onto said guide member and said transverse pressure bar if a filling or core of the set is missing from said pressure plate, said guide member, said transverse pressure bar, said equalizing means and said press plungers forming a unit, means for securing and guiding said unit, means for controlling the distance of said unit relative to said press plate, and means for periodically compressing said bellows chambers and for reciprocating said securing means together with said unit with respect to said press plate and the fillings or cores thereon.

KARL KEHRBECK.
